V. C. ANDERSON

CARBURETOR VAPORIZER

Filed July 21, 1923

UNITED STATES PATENT OFFICE.

VIRGIL CHARLIE ANDERSON, OF SAN FRANCISCO, CALIFORNIA, ASSIGNOR OF ONE-HALF TO CHARLES T. H. WRIGHT, OF SAN FRANCISCO, CALIFORNIA.

CARBURETOR VAPORIZER.

Application filed July 21, 1923. Serial No. 653,043.

To all whom it may concern:

Be it known that I, VIRGIL C. ANDERSON, a citizen of the United States of America, residing at San Francisco, in the county of 5 San Francisco and State of California, have invented certain new and useful Improvements in Carburetor Vaporizers, of which the following is a specification.

This invention relates to a carburetor 10 vaporizer for use with internal combustion engines, wherein provision is made for delivering the fuel under suction in a thin film-like stream while being subject to a heating action, with the flow control regulated entirely by the suction.

Another object of the invention is the provision of an air valve serving for the admission of air during operation of the engine under other than idling speeds, this 20 air valve being gravity closed and opened solely by the suction of the engine.

A further object of the invention is the provision of a manually controlled low speed or idling air inlet, arranged to deliver the 25 air in a mixing chamber to insure a proper mixture for idling speeds.

A further object is the provision of a fuel feed control operated by gravity and arranged to insure an opening movement in 30 proportion to and corresponding accurately with the suction of the engine.

The invention is illustrated in the accompanying drawings, in which:

Fig. 1 is a vertical sectional view of the 35 improved carburetor vaporizer, showing the same connected to the intake manifold.

Fig. 2 is a section on line 2--2 of Fig. 1, the air valve being omitted.

The improved carburetor vaporizer includes a casing 1, formed at the lower end 40 with an inwardly projecting annular flange 2, formed on its upper surface near the inner edge to provide a valve seat 3, the lower edge of this flange being inwardly and upwardly curved to form in effect an air inlet 4. A fuel tube 5 is arranged centrally of the casing 1, being supported at the lower end by integral laterally projecting strips 6, which are terminally secured to the lower 45 surface of the flange 2, as by bolts 7. These strips 6 are arranged in diametrically opposed pairs, and thus provide a material opening between the strips serving to admit air at the bottom of the carburetor vaporizer.

This air inlet will be hereinafter termed 55 the high speed air inlet. The fuel tube 5 extends below the supporting strips 6 as a tubular section 8, the bore of which is enlarged at the lower end to provide a shoulder 9. Arranged in the fuel tube 5 is a 60 heating element 10 preferably in the form of a hollow cylinder having its lower end bent laterally to provide a flange 11 to bear against the shoulder 9, a locking ring 12 threaded within the lower end of the tubular section 8 securing the heating element in place. The heating element extends lengthwise the fuel tube 5 and is of slightly less diameter than the interior of said tube, thereby defining a narrow annular fuel channel 13 about the heating element, which the fuel must traverse in its flow toward the engine. An insulating plug 14 is secured in the lower end of the heating element 10, 70 being preferably threaded within the locking ring 12. To this plug 14 is secured a wire or like member 15 arranged to be connected by a binding post 16 or the like secured to the plug 14, to a source of electric energy, so that the wire 15 may become 80 heated and thereby heat the element 10 for directing heat to the thin film of fuel flowing by such element.

The fuel is admitted through a pipe 17 leading into the fuel channel 13 immediately 85 above the lower end of the heating element, and this pipe 17 may, if desired, be interrupted by an auxiliary or preliminary heating element in the form of an insulated cylindrical block 18 arranged transverse the 90 pipe 17, preferably in a cylindrical transverse enlargement of said pipe, which enlargement is open at one end to receive a plug 19, from which the heating wire 20 projects and is coiled about the block 18, 95 the plug 19 having the usual binding post connector 21 for the service conductor.

It is to be understood that the preliminary heater may or may not be used for the preliminary heating of the fuel, and if used, the incoming fuel is caused to flow about the block 18 before reaching the fuel channel 13, and is preliminarily heated to thereby render its vaporization more complete in the fuel channel under some circumstances of 100 fuel use. Ordinarily, the main heater 15 is sufficient for the vaporization of the fuel, but under extreme weather conditions, or the

use of low grade fuel, it may be found desirable to use the auxiliary or preliminary heater.

The upper end of the fuel tube 5 above the heating element 10 is provided with a jet block 22 having a reduced lower end adapted to thread into the upper end of the fuel tube. This jet block has a comparatively minute fuel opening 23 arranged centrally and vertically thereof, the upper surface of the block above the fuel opening or passage 23 being formed with a divergent or inverted cone-shaped outlet 24. A conical valve 25 ground to accurately fit the conical outlet 24 is loosely seated in said outlet, so that in its lowered position the flow through the fuel passage 23 is cut off. A ball 26 having a diameter slightly less than the maximum diameter of the outlet 24, is arranged to seat upon an upstanding projection 27 from the fuel valve 25, a cage 28 secured to the jet block 22 aided by a light spring 29, carried by the cage, and bearing on the ball 26, serving to prevent undue displacement of the ball when the fuel valve 25 is open under the suction of the engine. The fuel passage 23 is manually controlled by a cut-off 30 mounted in and operative externally of the walls of the casing 1. A high speed air inlet, heretofore described as formed by the opening between the strips 6 and within the flange 2, is controlled by a weight valve 31 slidably mounted upon the fuel tube 5 and having its under surface formed to 35 cooperate with the valve edge 3 of the flange 2. Under those speeds of the engine inducing sufficient suction in the interior of the casing 1, the high speed air valve 31 is elevated from its seat proportionate to such 40 suction, to admit the necessary quantity of air. There is also provided a low speed air inlet, or what may be termed the idling speed air inlet. This comprises a tubular member 32, having a flaring inlet 33, and 45 supported in a threaded opening 34 in the casing 1, this low speed air inlet leading directly to and passing through an opening 35 in the jet block 22 so as to deliver the air through this low speed air inlet directly 50 to the fuel as it passes the valve 25. This low speed air inlet is manually controlled by a cut-off 36. A pressure relief valve 37 is mounted in an outlet 38 from the casing 1, this valve opening outwardly and being 55 normally held closed by a spring 39. Valve 37 affords relief from internal pressure in the event of a back fire.

The casing 1 may, and preferably is, attached to the section 40, which in turn 60 is connected to the intake manifold 41, the section 40 containing the usual throttle valve 42.

The space immediately above the fuel valve 25 constitutes a mixing chamber, the 65 fuel passing freely through the cage 28 and

being directed and diverted by the valve and overlying ball into a thin stream, which is taken up by the air rising directly through the high speed air inlet. An intimate mixture is thus secured in a comparatively short 70 length of mixing chamber.

The fuel prior to reaching the control valve 25, is adapted to travel as a thin annular stream lengthwise the heating element 10, and as the latter is heated by the electric 75 current as described, it will be apparent that the fuel is substantially vaporized before it reaches the fuel passage 23. The suction of the engine therefore controls the fuel valve 25 and also the high speed air inlet valve 80 31, and with the respective inlets proportionately arranged, it is apparent that a uniform and substantially constant-proportion mixture will be maintained at all times without regard to the quantity of such mix- 85 ture used by the engine in operation.

Claims:

1. A carburetor vaporizer for internal combustion engines, comprising a casing 90 having a fuel tube therein, a cylindrical heating element arranged within and spaced from the interior of the fuel tube to define a narrow fuel channel lengthwise said tube, means for heating said element, a fuel jet passage arranged at the end of the fuel tube, a gravity operated valve for controlling said passage, and means bearing on said valve and serving as a fuel spreader beyond the 95 valve.

2. A carburetor vaporizer for internal 100 combustion engines, comprising a casing having a fuel tube therein, a cylindrical heating element arranged within and spaced from the interior of the fuel tube to define a narrow fuel channel lengthwise said tube, 105 means for heating said element, a fuel jet passage arranged at the end of the fuel tube, a gravity operated valve for controlling said passage, and a ball to bear upon said valve to assist in seating the same, said ball acting as a fuel spreader beyond the valve.

3. A carburetor vaporizer for internal 110 combustion engines, comprising a casing 115 having a fuel tube therein, a cylindrical heating element arranged within and spaced from the interior of the fuel tube to define a narrow fuel channel lengthwise said tube, means for heating said element, a fuel jet passage arranged at the end of the fuel tube, a gravity operated valve for controlling said 120 passage, and a gravity valve controlled air inlet at the lower end of the fuel tube.

4. A carburetor vaporizer for internal 125 combustion engines, comprising a casing formed with an air inlet at the open end, a fuel tube extending vertically and centrally of the casing, an air valve slidably mounted on the fuel tube and controlling said air inlet, a fuel passage at the upper end of the fuel tube, gravity operated means for con- 130

trolling said fuel passage, means arranged above the fuel passage for compelling a divergent course of the fuel, and means for delivering air directly into the fuel in this 5 divergent path.

5. A carburetor vaporizer, comprising a casing having an air inlet at the lower end, a fuel tube arranged in the casing, a gravity operated valve slidably mounted on the fuel 10 tube to control said air inlet, a jet block secured to the upper end of the fuel tube, a heating element arranged within the fuel tube and extending adjacent the jet block, the fuel passage through the jet block being 15 upwardly divergent throughout the upper portion thereof, a conical valve seated in said divergent passage and controlling the fuel passage through the jet block, and a ball having a diameter corresponding to the 20 maximum diameter of the divergent fuel passage and resting upon the valve.

6. A carburetor vaporizer, comprising a casing having an air inlet at the lower end, a fuel tube arranged in the casing, a gravity 25 operated valve slidably mounted on the fuel tube to control said air inlet, a jet block secured to the upper end of the fuel tube, a heating element arranged within the fuel

tube and extending adjacent the jet block, the fuel passage through the jet block being 30 upwardly divergent throughout the upper portion thereof, a conical valve seated in said divergent passage and controlling the fuel passage through the jet block, a ball having a diameter corresponding to the 35 maximum diameter of the divergent fuel passage and resting upon the valve, and a cage carried by the jet block and limiting the play of the ball.

7. A carburetor vaporizer for internal 40 combustion engines, comprising a casing having a fuel tube therein, open at the upper end, a cylindrical heating element arranged within and spaced from the interior of the fuel tube to define a narrow fuel channel 45 lengthwise said tube, means for heating said element, a fuel jet block removably secured in the open end of the fuel tube and formed with a fuel passage, a gravity operated valve for controlling said passage, a fuel spreading ball seating on said valve, a fuel pipe leading from a source of supply to said fuel channel, and a preliminary fuel heater arranged in said pipe beyond the casing.

In testimony whereof I affix my signature.
VIRGIL CHARLIE ANDERSON.
